SPRAY GUN

Theodore C. Leisenring, 1253 S. High St.,
Denver, Colo. 80210

Filed May 8, 1969, Ser. No. 17,077

Term of patent 14 years

Int. Cl. D23—01

U.S. Cl. D23—17

FIG. 1 is an elevational side view of a spray gun showing my new design;

FIG. 2 is a front view thereof;

FIG. 3 is a rear view thereof; and

FIG. 4 is a top view thereof.

I claim:

The ornamental design for a spray gun, as shown and described.
